UNITED STATES PATENT OFFICE.

CLARENCE WARNER, OF DAYTON, OHIO, ASSIGNOR TO DELCO-LIGHT COMPANY, OF DAYTON, OHIO, A CORPORATION OF DELAWARE.

PUMPING APPARATUS.

Application filed November 26, 1923. Serial No. 677,139.

This invention relates to pumping apparatus, and more particularly to that type of apparatus in which reciprocating pump rods are employed.

5 It is among the objects of the present invention to prevent mixing of the fluid being pumped with lubricant supplied to the pump driving mechanism, or vice versa.

Further objects and advantages of the 10 present invention will be apparent from the following description, reference being had to the accompanying drawings, wherein a preferred form of embodiment of the present invention is clearly shown.

15 In the drawings:

Fig. 1 is a view partly in elevation and partly in section of a pumping apparatus embodying the present invention.

Fig. 2 is a sectional view taken on the 20 line 2—2 of Fig. 1.

Referring to the drawings, a gear housing 20, which provides a lubricant chamber 21, supports an electric motor 30. Motor shaft 31, provided with a worm 32, extends 25 into the gear housing 20 and is journalled in bearings 33 and 34 supported within said housing. A flywheel 35 is secured to the end of motor shaft 31 and is accessible for removal through an aperture 22 in housing 20 which is closed by a removable cover 23.

An aperture 24 in the top of housing 20 is provided with an annular cover or frame 40 having an apertured boss or bearing 41 15 extending from said housing 20 through aperture 44 in the top of frame 40. Frame 40 provides an annular chamber 42 surrounding bearing 41, which may be drained by connecting a suitable drain cock with 0 opening 43 in a wall of said chamber. An annular flange 45, on frame 40, is received 5 within a frame 50 which is secured to frame 40 by bolts 51.

Frame 50 supports a pump cylinder 60, 5 having a pump rod 61 adapted to be reciprocated within said frame 50, directly above the gear housing 20. Frame 50 is provided with openings 52 for permitting access to the pump rod 61. A substantially cylindrical shaped frame 55 is located within frame 50 and is rotatably supported by flange 45 on frame 40. Frame 55 may be rotated by a handle 57 for closing openings 52 in frame 50 to prevent access to pump rod 61, or to 5 bring openings 56 into alignment with open-

ings 52 to permit access to said pump rod. Frame 55 is provided with openings 58 adjacent the bottom edge thereof.

A shaft 70, supported within gear housing 20 at right angles to shaft 31, carries a worm gear 71 which is driven by worm 32. An eccentric 72, carried by gear 71, is provided with an eccentric strap 73 which functions as a connecting rod for reciprocating a cross head 75 through apertured boss or bearing 41. Pump rod 61 is secured to cross head 75, and the reciprocatory movement of said cross head is transmitted to rod 61, to operate the pump.

A cup shaped member or baffle 80, having a flange 81, is secured between the cross head 75 and the pump rod 61 and is adapted to be reciprocated within frame 55 by said rod 61. Flange 81 is adapted to extend into the chamber 42 surrounding bearing 41, upon the downward stroke of rod 61, as clearly shown in Fig. 1.

Mode of operation.

When the motor 30 is operated, worm 32 drives worm gear 71 which in turn drives eccentric 72, and eccentric strap 73 causes cross head 75 to be reciprocated through bearing 41, and this reciprocatory movement is transmitted to the pump rod 61. At 80 the same time, the baffle 80 is reciprocated within frame 55 in response to the movement of the pump rod 61. Any liquid which may escape from the cylinder 60 around the pump rod 61, will trickle down rod 61 and strike baffle 80 and be deflected thereby into the chamber 42, and be prevented from working its way between cross head 75 and bearing 41 into the lubricant chamber 21. Any lubricant tending to work its way from 85 chamber 21 between cross head 75 and bearing 41, will be deflected into chamber 42 by the inner surface of baffle 80, which entirely surrounds the top edge of bearing 41, and in this manner the lubricant will be prevented 90 from coming into contact with the pump rod 61.

While the form of embodiment of the present invention as herein disclosed, constitutes a preferred form, it is to be understood that other forms might be adopted, all coming within the scope of the claims 95 which follow.

What is claimed is as follows:

1. Pumping apparatus comprising, in 119

- combination, a pump cylinder including a pump rod; a gear housing; an apertured frame separating the pump cylinder and gear housing; driving mechanism within the gear housing; means for connecting the driving mechanism and pump rod; and baffle means carried by the pump rod so as to be on the cylinder side of the apertured frame at all times, for deflecting upon said frame fluid escaping from either the pump cylinder or the gear housing.
2. Pumping apparatus comprising, in combination, a pump including a cylinder and pump rod; a gear housing; a frame separating the pump cylinder and gear housing; said frame having an apertured extension toward the cylinder; driving mechanism within said gear housing; connecting means between the driving mechanism and pump rod; and means interposed between the pump rod and connecting means, and including a portion adapted to surround the apertured extension whereby fluids escaping from either the pump or the gear housing will be deflected upon said frame and outside of the apertured extension.
3. Pumping apparatus comprising, in combination, a pump rod, a gear housing, an apertured boss extending from said gear housing, a cross head received by said apertured frame for connecting the driving mechanism and pump rod, and a baffle movable with the pump rod having a flange adapted to surround the bearing and cross head and extend into the chamber for deflecting a liquid escaping from the pump around the pump rod and liquid escaping through the bearing around the cross head into said chamber from where it may be drained.
4. Pumping apparatus comprising, in combination, a pump rod, a gear housing, driving mechanism within said housing, a cover for said housing providing a bearing and an annular chamber surrounding the bearing, a cross head received by said bearing for connecting the driving mechanism and pump rod, and a baffle movable with the pump rod having a flange adapted to surround the bearing and cross head and extend into the chamber for preventing a liquid escaping from the pump around the pump rod, from being deposited onto said boss and cross head and for preventing liquid escaping from the gear housing through said aperture around the cross head from contacting with the pump rod.

In testimony whereof I hereto affix my signature.

CLARENCE WARNER.
